ATTORNEYS

UNITED STATES PATENT OFFICE.

CHAPMAN JAY ROOT, OF TERRE HAUTE, INDIANA.

DESIGN FOR A BOTTLE OR SIMILAR ARTICLE.

• 54,682.

Specification for Design.

Patented Mar. 9, 1920.

Application filed September 29, 1919. Serial No. 327,327. Term of patent 14 years.

To all whom it may concern:

Be it known that I, CHAPMAN JAY Root, a citizen of the United States, residing at Terre Haute, in the county of Vigo and State of Indiana, have invented a new, original, and ornamental Design for Bottles or Similar Articles, of which the following is a specification, reference being had to the accompanying drawing, forming a part thereof.

The figure is a side elevation of a bottle showing my design.

I claim:

The ornamental design for a bottle or similar article, as shown.

CHAPMAN JAY ROOT.
